Jul 25, 1832

To all to whom these presents shall come: Be it known
that I, James Bennett of the town of Petersburgh, County of
Cayuga and State of New York, have invented a new and
useful improvement in a cooking machine for roasting,
baking and frying meats, and for baking bread and pies
and past cakes; And that the following is a full and exact
description of the construction and operation of the said machine,

as mounted or improved by me. The machine consists of a wrought or hot metal bottom to be about as wide as and as it is long, to be made with or without legs. The arms to project up high enough to answer the purpose of a gridiron, spider or han. The front part to have a lip in it for the purpose of pouring out gravy. The back part to have an ear on each corner to extend above the top of the arm about one and a fourth inch. The one ear to have a hole in it and the other a slit with a hook attached to it to turn over, a wire is attached to the bottom part of the arm to fasten it to the bottom. There is to be an ear on each end to admit in a hole which is to extend far enough above the top of the arm to be convenient to handle it.

The oven is to be made of tin, the back and ears are to be made oval so that a small bottom will admit of a large oven. There is to be a rod or spit passing through the meat to be baked or roasted in the same, which may be removed, and two other rods inserted for the purpose of setting on pins for baking bread or pies. There may also be hooks placed in the upper part of the oven for the purpose of roasting fowls or chickens. The oven may be removed and a grid iron attached to the same ears and by the same hook for the purpose of toasting bread, warming and boiling meat. Said grid iron is to be constructed in the same as in flat iron, and to stand in an elevated manner over the side so as to conduct the gravy into the bottom of the machine, which serves as a dripping pan. The grid iron is to have a tin reflector, attached to the lower end by a wire to shut over the meat to keep off dust, and draw the heat, or as to cause both sides to cook at the same time. The grid iron is to have a strap attached to it with notches in the same to catch in a hook attached to the side of the basin, to elevate it as occasion may require. The back part of the bottom is to have in it a hook which serves as a handle for pouring out the gravy and also as a foot or
